UNITED STATES PATENT OFFICE.

WILLIAM K. COCHRAN, OF SPRINGFIELD, OHIO.

METALLIC FILING-CASE.

1,268,063.

Specification of Letters Patent. Patented May 28, 1918.

Application filed August 11, 1915. Serial No. 44,868.

To all whom it may concern:

Be it known that I, WILLIAM K. COCHRAN, a citizen of the United States, residing at Springfield, in the county of Clark and State 5 of Ohio, have invented certain new and useful Improvements in Metallic Filing-Cases, of which the following is a specification.

My invention relates to improvements in metallic filing cases, the primary object being to provide a generally improved metallic filing or transfer case particularly designed and adapted to be stacked upon and to interlock with a subjacent case or unit to form suitable tiers as required in the transfer or 15 filing and preservation of letters, documents, and the like.

A further object of the invention is the provision of an improved light weight reinforced metallic case body, the present embodiment being particularly designed and adapted for use as a metallic transfer case.

A still further object is the provision of an improved metallic filing drawer or receptacle together with improved means of 25 mounting and securing such filing drawer in the case body.

A still further object is the provision of an improved metallic follower for a filing drawer together with improved means for 30 detachably securing and adjusting such follower in the drawer.

With the above mentioned and other ends in view, the invention consists in the novel construction, arrangement, and combination 35 of parts, hereinafter described, illustrated in some of its embodiments in the accompanying drawings, and particularly pointed out in the appended claims.

Referring to the drawings forming a part 40 of this specification, Figure 1, is a perspective view of the improved filing case or unit and illustrating the manner in which one case or unit may be stacked upon and interlocked with another or subjacent unit.

Fig. 2, a reduced rear elevation of the same, particularly illustrating the improved flanged drawer protecting stops at the rear.

Fig. 3, a cross sectional view taken on line 3—3 of Fig. 1.

Fig. 4, a perspective view of the improved filing drawer or receptacle, removed, certain portions being broken away for the purpose of clearer illustration of the parts.

Fig. 5, a reduced plan view of one of the 55 drawer head blanks before being formed up.

Fig. 6, a view of the metallic blank for forming the case or unit body.

Fig. 7, an enlarged perspective view of one of the lower front corners of the case or unit equipped with a drawer sustaining 60 roller for coöperating with the friction bearing or side runner portion of the improved drawer.

Similar numerals of reference designate like parts throughout all the figures of the 65 drawings.

The improved metallic filing case comprises an open or double ended case body formed of a single blank of sheet metal and notched and folded along the lines indicated 70 in Fig. 6, to form a top 1, and sides 2, the latter terminating, in the present instance, in inwardly projecting drawer sustaining slide ways 2^a, said slide ways, in the present instance, being spaced apart to form an open 75 bottom or recess normally closed by the improved metallic filing drawer or receptacle hereinafter described.

The metallic blank forming the top and sides of the case body is provided with suitable notches 2^b, (see Fig. 6) along the lines to be folded to form the upper corners of the case body, and is also provided with corner notches 2^c, said notches 2^b, and 2^c, corresponding in depth to the marginal portions 85 2^d, and 2^e, at the opposite ends of the blank whereby said marginal portions are adapted to be folded inwardly and outwardly, respectively, for the purposes now mentioned.

Upon reference to Fig. 2, it will be seen 90 that the marginal portions 2^d, are bent inwardly to form flanged drawer protecting stops adapted to abut against the marginal edges of the rear drawer head and not only stop the drawer in its normal or closed position but to exclude the contents of such drawer from foreign substances such as dirt, dust, and the like.

As a means of supporting and reinforcing the top and sides of the case body as well as 100 adapting the latter to be stacked upon and interlocked with the adjacent case or unit, the ends of the case body are surrounded and suitably secured to a channel bar supporting frame 3, the latter being preferably electrically welded to the walls of the case body and the free ends preferably meeting at the bottom of the case as at 3^a, and are suitably secured to each other by electric welding after the channel bar is bent into suitable 105 110

form to form the frame. It will be apparent upon reference to Fig. 1, that the front marginal portions 2^e, of the top and sides of the case body are bent upwardly and outwardly, 5 respectively, to engage with the front edges of the front frame.

As a means of adapting the case body or unit to be stacked upon and to interlock with another or subjacent unit as indicated in 10 Fig. 1, of the drawings, the lower portions of the channeled sides of the supporting frames are provided with interlocking filler bars or members 4, depending or projecting downwardly to form sanitary supporting 15 legs for the first or lowermost case or unit, and to form interlocking or stacking members adapted to be received and seated in the upper portions of the side channels of the subjacent supporting frames of a subjacent 20 case or unit when stacked.

As a means of stopping the drawer or receptacle when fully withdrawn to its open position as well as assisting in excluding dust and dirt from the drawer contents when 25 closed, the front portion of the top of the case body is provided with a depending or flanged drawer stop 5, the latter being adapted to be engaged by the upper marginal edge of the rear drawer head when the 30 drawer is fully withdrawn and when the drawer is moved to its closed position the upper marginal edge of the front drawer head is adapted to come into engagement with and cover the same as clearly shown in 35 Fig. 1, of the drawings.

The improved metallic filing drawer or receptacle comprises a bottom section 6, provided with median and side channel runners 6^a, and 6^b, respectively, said bottom section 40 being also provided with vertical sides 6^c, terminating at their top in reinforced or hemmed edges 6^d.

The front and rear drawer heads 7 and 8, respectively, are each formed of a single 45 blank of sheet metal notched at the corners and adapted to be folded along the lines indicated by dotted lines in Fig. 5, of the drawings so as to form marginal side and bottom portions 7^a, and 8^a, respectively, 50 adapted to be bent inwardly and welded to the bottom and side portions or sections 6 and 6^c, of the drawer, the upper marginal portions 7^b and 8^b, of the drawer heads being preferably bent downwardly to form a protecting edge or hem as shown. The drawer 55 heads 7 and 8, are preferably further strengthened and reinforced by means of side bars or strips 9, which latter also act to properly protect and support the drawer 60 contents, as well as affording ready access to the latter and saving material in the drawer construction.

It will be observed that the side channel runners or skids 6^b, of the improved drawer 65 rest upon and coöperate with the drawer sus-

taining slide ways 2^a, of the sides of the case body and coöperate with such slide ways in forming a proper support and sliding surface for the improved drawer, the contact portion or joint formed between the slide ways 2^a, and the runners or skids 6^b, acting not only to lessen friction in the movements of the drawer but also serving to exclude dust and dirt from the drawer contents. The central or median runner or section 6^a, 70 not only serves to reinforce this portion of the drawer but forms a suitable channel or slide way for receiving and containing the follower rod 10, and the follower securing lugs or members 11, of the improved metallic 75 follower to be now described.

The metallic follower 12, is formed of a single blank of sheet metal bent upon itself at its base to form a horizontally extending supporting base or section 12^a, the latter 80 being adapted to slide upon the bottom section 6, preferably welded to the intermediate portion 11^a, of the securing lugs or members 11, as shown, it being also apparent that, in the present instance, the follower securing 85 members correspond substantially in dimensions to the median runner or panel section 6^a, thereby more effectively guiding the follower 12, and such vertical follower is preferably reinforced at its top by means of a 90 reinforcing hem 12^b, as shown most clearly in Fig. 4 of the drawings.

As a means of removably mounting the follower rod within the filing drawer the inner lower portions of the drawer heads are 100 provided with depending spring tongues 13, welded or otherwise suitably secured to the drawer heads, the lower or free ends of said spring tongues being provided with openings 13^a, adapted to removably receive and 105 contain the ends of the follower rod, it being apparent that the ends of such rod may be readily inserted or removed by pressure upon the free ends of the depending spring tongues.

If desired the lower front corners of the case body may be provided with drawer sustaining rollers 14, mounted in struck out depending lugs 15, of the front portions of the slide ways 2^a, and adapted to coöperate with 115 the side runners 6^b, of the drawer, as illustrated in Fig. 7, of the drawings, such rollers 14, acting to still further eliminate friction in the opening and closing movements of the drawer.

From the foregoing description, taken in connection with the accompanying drawings, the operation and advantages of my invention will be readily understood.

Having thus described some of the embodiments of my invention, what I claim and desire to secure by Letters Patent, is,—

1. A metallic filing case, comprising an open bottom open ended case body provided with surrounding end frames, and a drawer 130

- having bottom and end sections normally closing said open bottom and ends, respectively.
2. A metallic filing case, comprising a single blank of sheet metal formed into top and side sections, said side sections terminating in drawer sustaining slide ways spaced from each other forming an open bottom, end frames surrounding said top and side sections and extending across said open bottom, and a drawer having a bottom section provided with side runners mounted on said slide ways and provided with heads normally forming the ends of said filing case.
3. In a metallic filing case, a blank adapted to be folded along predetermined lines to form top and side sections and provided with notches opposite said predetermined lines of fold and having notched corners forming marginal portions at the front and rear adapted to be bent into front and rear flanges, the sides of said blank being provided with marginal portions adapted to be bent inwardly to form drawer sustaining slide ways when the case body is formed.
4. A metallic filing case, comprising integral top and side sections terminating at their front and rear in marginal strips, said marginal strips at the rear being bent inwardly forming flanged drawer protecting strips and said marginal strips at the front being bent outwardly forming frame securing and reinforcing members, and a metallic drawer having heads forming the ends of said filing case, said rear drawer head having its open marginal edges normally covered by said drawer protecting stops.
5. In a metallic filing case, the combination with an open bottom open ended case body provided with end flanges, and surrounding end supporting frames abutting against and engaged by said end flanges; of a drawer having bottom and end sections normally closing said bottom and ends of said case body, respectively, and engaged by said end flanges when closed.
6. A metallic filing case, comprising an open bottom open ended case body formed of a single blank of sheet metal provided with stop flanges projecting within said open ends, and a drawer having bottom and end sections forming the bottom and ends of said case body and abutting against said stop flanges when closed.
7. A metallic filing case, comprising an open bottom open ended case body formed of a single blank sheet of metal and provided with end flanges forming drawer stops and terminating in inwardly extending drawer sustaining slide ways at the sides of said open bottom, and surrounding end supporting frames extending across said open bottom and supporting said drawer sustaining slide ways.
- In testimony whereof I have affixed my signature in the presence of two witnesses.

WILLIAM K. COCHRAN.
